PORCH LIGHT AND NUMBER DISPLAY

Carl Lorretske, Seattle, Wash.

Application May 13, 1937, Serial No. 142,517

2 Claims. (Cl. 40—130)

This invention relates to an illuminated porch light, that is, an electric bulb equipped accessory in the nature of an attachment expressly designed to be attached to the ceiling of the porch at a point of vantage to conveniently display the identifying number of the residence.

The principal object of the invention is the provision of a simply constructed device designed to aid pedestrians and others in locating a particular residence by its street number.

In keeping with the primary requisites of simplicity and practicability, the preferred embodiment of the invention comprises a ceiling hanger or canopy functioning somewhat as a reflector, this being provided with depending end plates which features serve collectively to support a glass panel so made as to provide a holder for detachable interchangeable identifying numerals.

Other features and advantages will become more readily apparent from the following description and drawings.

In the drawings, wherein like numerals are employed to designate like parts throughout the views:

25 Figure 1 is a front elevation of a structure developed in accordance with the principles of the present invention showing how the device appears and how it is hung from a porch ceiling or the like.

30 Figure 2 is a top plan view of the device per se seen in Figure 1.

Figure 3 is a transverse or cross-sectional view taken approximately on the plane of the line 3—3 of Figure 1.

35 Figure 4 is a horizontal detail fragmentary section which may be said to be taken substantially on the plane of the line 4—4 of Figure 1.

Figures 5 and 6 are fragmentary perspective views of features of the complete assembly.

40 Figure 7 is a fragmentary perspective view of one end of the number unit or frame, and

Figure 8 is a perspective view of one of the end members of said unit or frame.

Referring now to the drawings by distinguishing reference numerals, it will be observed that the main supporting or hanger plate is in the nature of a pyramidal canopy, this being denoted by the numeral 7. It is of general rectangular form and provided at its corner portions with integral L-shaped attaching members 8. These are properly constructed to facilitate attachment to porch ceilings or equivalent supports 9. The numerals 10 designate substantially triangular end plates, the horizontal flanges 11

55 of which are bolted or otherwise fastened as at

12 to the under side of the ends of said plate 7. The vertical flanges 13 serve as convenient supports for the number frame or unit 14. This unit 14 is of general rectangular form and comprises a sheet metal, supporting frame 15 having upper and lower edge channel members 15a and 15b in the rear thereof substantially rectangular in cross-section and longitudinally slotted as at 15c to accommodate the glass panel or lens 16. Sheet metal end members 15d of right angled 10 form in cross-section fit at their ends between the members 15a and 15b, as shown in Figure 7, behind the front of the frame 15. The front of said frame 15 is extended at the ends thereof beyond the members 15d to provide ornamental 15 extensions 17. The described unit 14 is secured to the flanges 13 by bolts 18 passing through bolt holes 15e and 15f in the ends of the frame 15 and the end members 15d, respectively, whereby the latter are clamped in position relative to the 20 members 15a and 15b. The ends of the lens 16 bear against the bolts 18, as shown in Figure 4, whereby said lens is held against endwise shifting.

The identification numerals which are assembled in groups are individually denoted by the 25 reference numerals 19. They are of standardized proportions and each numeral has at its top a retention lug 20. This fits slidably up into a correspondingly shaped slot 25 in the upper member 15a of the supporting frame 15. At its lower 30 end each numeral is provided with a depending retention extension or complementary lug 21 having a projection 22 which may be described as a detent. The lug 21 fits into the main keeper seat 23 in the lower frame member 15b, while 35 the detent is seated in the auxiliary keeper notch 24. By having the double notch features 23 and 24 in the lower frame member, and slipping the lugs 20 at the top up into slots provided therefor in the upper frame member, I provide convenient means for assembling the numbers to provide the collective residence identification. Hence, it will be seen that the identifying house numbers 19 are detachably supported in the frame 14 and rest against the outer surface of the transparent glass panel 16. The panel 16 is illuminated on dark days or at night by an appropriate, horizontally elongated electric bulb 25 supported on one of the end plates 10 and disposed in parallelism with the inner or rear face of the 40 panel.

In practice the lugs 20 on the identification numbers 19 are slipped up into the slots 25 and then allowed to drop down so that the detents 22 rest in the keeper slots or notches 24. This 45 55

provides a convenient arrangement whereby the average house owner can purchase his own identification numbers and put them in place.

It is thought that the description taken in connection with the drawings will enable a clear understanding of the invention to be had. Therefore, a more lengthy description is thought unnecessary.

While the preferred embodiment of the invention has been shown and described, it is to be understood that minor changes coming within the field of invention claimed may be resorted to if desired.

I claim:

- 15 1. In a device of the class described, a suspension plate constituting a canopy and provided at its corner portions with hanger members, a pair of end plates attached to and depending at right angles from the end portions of said suspension plate, said end plates being provided with attaching flanges, a frame detachably bolted to said attaching flanges and disposed at right an-

gles to the end plates and depending at right angles in relation to said suspension plate, a glass plate supported in said frame, and an electric bulb supported on one of said end plates and disposed parallel to said glass plate.

2. In a device of the class described, a suspension plate constituting a canopy and provided at its corner portions with hanger members, a pair of end plates attached to and depending at right angles from the end portions of said suspension plate, said end plates being provided with attaching flanges, a frame detachably bolted to said attaching flanges and disposed at right angles to the end plates to depend at right angles from said suspension plate, a glass plate supported in said frame, number simulating members detachably secured in said frame along side said glass plate, and an electric bulb supported on one of said end plates and disposed parallel to said glass plate.

CARL LORBETSKE.
